UNITED STATES PATENT OFFICE

LOWI EDWARDS, OF BOSTON, MASSACHUSETTS

LIFEBOAT-HANDLING MECHANISM

Application filed March 21, 1929. Serial No. 348,948.

- This invention relates to mechanism for rapidly and expeditiously handling life boats. It is aimed to provide a novel disappearing construction adapted to be carried by a vessel.
- 5 Another important object is to provide a construction wherein the casing is rotatable and mainly disposed below a deck and which has articulate sections adapted to be projected and substantially form an arc for better coaction with life boats and which sections are adapted to assume a straight line when in retracted or disappeared position.
- 10 Another object is to provide a novel construction wherein the casing carries a motor and coacting parts whereby the casing may be rotated and whereby the disappearing structure may be actuated and raising and lowering mechanism for the life boats may be actuated.
- 15 20 The more specific objects and advantages will in part be pointed out and otherwise become apparent from a consideration of the description following taken in connection with accompanying drawings illustrating an operative embodiment.
- 25 In said drawings:—
- Figure 1 is a view showing the device in elevation, partly broken away, as in use;
- 30 Figure 2 is a view similar to Figure 1 taken at a right angle thereto and looking from the right in Figure 1;
- 35 Figure 3 is an enlarged sectional view taken on the line 3—3 of Figure 1;
- Figure 4 is an enlarged sectional view taken on the line 4—4 of Figure 2.
- 40 Figure 5 is a view in central vertical section somewhat similar to Figure 1 but showing the parts in disappeared or retracted position,
- 45 Figure 6 is a side elevation of a plurality of davit sections,
- Figure 7 is a view of said davit sections of Figure 6 taken at a right angle thereto,
- 50 Figure 8 is a plan view of one of the davit sections,
- Figure 9 is a sectional view taken on the line 9—9 of Figure 1,
- 55 Figure 10 is a sectional view taken on the line 10—10 of Figure 1, and
- 60 Figure 11 is a detail view of the top section of the davit.
- 65 Referring specifically to the drawings, 10 designates fragmentarily the deck of a ship, above which life boats of the type shown in Figure 1 are carried in the usual manner. Suitably fastened in an opening in the floor 10 is a collar or bearing 12 in which a tubular casing 13, preferably of a suitable metal, is journaled. Such casing 13 is mainly disposed below the deck 10 and its lower end is supported and journaled in a base or bearing 14 fastened as at 15 to a suitable part in the ship or vessel.
- 70 As best shown in Figure 5, casing 13 normally houses a davit generally designated 16 only life boat engaging parts being exposed or extending above the deck 10. Such davit 16 is adapted to be extended into the position shown in Figure 1 so that it may engage the life boat and the arrangement described therefore is a disappearing davit.
- 75 Rigidly fastened to and extending radially from the casing 13, slightly above the deck 10 is a platform or support 17 which rests on an annular rack or ring 18 arranged concentric with the axis of the casing 16 and secured to the deck 10. An electric motor or other approved prime mover as at 18' is carried by platform 17 and its main shaft 19 drives a bevel gear wheel 20 which is arranged in mesh with a bevel gear wheel 21 keyed to a shaft 22 vertically disposed and journaled on one side of the platform 17 and also having a gear wheel 23 keyed thereto which is in mesh with the teeth 24 of the aforesaid rack 18. It will be noted that the shaft 19 has a clutch 25 therein of conventional design whereby driving relation between the motor 18 and gear 20 may be established or cut out through the operation of a clutch actuating lever 26. It will be seen that when clutch 25 is in and motor 18 operating, that the gearing described will rotate casing 10 about its vertical axis, and thus move it to any position desired.
- 80 Reverting to the davit 16, the same has a lower section 27 which normally rests on diametrically opposite supports 28 arranged within the casing 13. The davit also includes
- 85 90 95 100

a top section 29 and any suitable number of intermediate sections 30. As shown in the drawings, the various davit sections 27, 29 and 30 are of skeleton or fabricated form, 5 preferably made from strips of metal. Along two longitudinal edges the said davit sections have interfitting hinge members which are joined by horizontal pintles or pivots. At the other longitudinal edges, adjacent to the 10 junction of the sections, brackets 33 and 34 are fastened in pairs to respective sections, the section 33 being rigidly connected together by transverse bars 35 and links 36 are pivotally connected to the brackets 33 and 15 pass through vertically elongated slots 37 of the brackets 34. By reason of this construction, the sections 27, 29 and 30 are capable of limited pivotal movement relatively to each other so that they may assume the alined position when retracted and may assume arcuate form shown in Figure 1, of their own weight, when projected.

The davit of its own weight tends to move and return to retracted position. In order 25 to project it, a cable 71 is anchored to a stud 39 suitably mounted at the base of section 27. Said cable 71 is trained over a guide pulley 40 below the same, which is carried by a bracket 41 loosely passing between bars 42 30 rigid with the casing 10 and which mount the bracket 41, a plate 43 being slidable on the rod 44 of the bracket, and a cushioning coil spring 45 being carried by the rod and engaging the plate 43 at one end and an abutment 46 on the rod at the other end. Said cable 71 then passes upwardly through a 35 guide sheath 66, over guide pulley 77^a and thence over a winding drum 78. Sheave 77^a is journaled on a shaft 50 fixed between side 40 bearings 51 rigid on the platform 17.

Said drum 78 is loose on a shaft 81' which is in turn journaled at one end in one of the walls 51 and at its other end has a sleeve 85 45 screw threaded thereon and in turn journaled in the adjacent side wall 51. Keyed to shaft 81' is a gear wheel 82 which has a friction clutch portion 83 arranged to engage a friction clutch recess 84 in the drum 78. By reason of this construction, while the drum 50 may be disengaged from the shaft 81', it may be brought into rigid relation therewith by turning the sleeve 85 against the same, thus causing the surfaces 83 and 84 to clutch or engage, in the latter condition being 55 uniformly connected with the gear 82 and shaft 81'. Gear 82 is constantly driven by a pinion 57 in mesh therewith and carried by a shaft 58 journaled in the side bearings 51 and having a pulley 59 thereon traversed by a 60 belt 60 which also traverses a pulley 61 carried by the main shaft 19 of motor 18.

The aforesaid sheath or plate 47 has a key rail 62 which is overlapped by lugs 63 carried 65 by the davit sections 27, 29 and 30 when the

latter are retracted within the casing 13. Also under such conditions, lug 64 on the same davit sections overlap guide rails 65 carried by a plate 66 fastened rigidly within and to the casing 13.

Adjacent the top of the davits a hook 67 is carried which is adapted to engage in eyelets 68 or the like of life boats in the handling of the latter, that is in raising or lowering the same into and out of the water or swinging them laterally across the deck 10. The hook 67 has a roller or pulley 69 pivoted to a pin 70 thereon and a cable 38 is trained over pulley 69 having one end anchored at 72 by an eye bolt to the section 29 of the 80 davit. Said cable 38 also passes over a guide pulley 73 journaled in bracket 74 carried by the section 29. Cable 38 thence passes into the casing 13 and over guide pulleys 75 passing through bars 76, then leaving behind the sheath 66, then being trained over guide pulley 48 and then being fastened to drum 49. Pulley 48 is journaled on a shaft 50 fastened to the bearing 51. Cables 80 are fastened at 81 to the section 27 of the davit, trained over the pulley 77 and fastened to the drum 78.

The drum 49 is loose on a shaft 52 which is journaled at one end in one of the side bearings 51, having a gear 54 thereon and also having coacting clutch portions 55 and 56 similar to those at 83 and 84, respectively. The other end of shaft 52 is screw threaded with a sleeve 53 and the latter is journaled in the other side bearing 51 and adapted for operation similar to the sleeve 85, to connect or disconnect the drum 49 relative to the shaft 52 so as to exert a positive action on the cable fastened thereto or to permit paying out thereof.

Cable 71 is wound on drum 78 opposite to the cables 80 so that when the davit is extended, cable 71 will wind off when cables 80 are winding on the drum. For that reason spring 45 is arranged under pulley 40 to keep an equal tension on cables 80 and 71.

A cable 90 suitably trained over pulleys 91 is then wrapped about six turns on drum 92 and then extends into casing 13 and has a weight 93 on same, heavy enough to keep the slack out of cable when the hook 67 is being raised after lowering a life boat.

A conventional brake 94 is connected to drum 92 so the operator can work it from his usual position to stop drum 92 from revolving which tightens cable 90 and upsets hook 67 which releases the life boat from the hook 67.

Various changes may be resorted to provided they fall within the spirit and scope 125 of the invention.

I claim as my invention:

1. In combination, with a deck, a casing 130 mounted for rotation and mainly disposed below the deck, a davit normally within the

casing means to rotate the casing, and means operable to project the davit.

5 2. In combination with a deck, a casing mainly disposed below the same, and a davit normally within the casing, and means operable to project the davit, said davit being in articulate sections arranged to move out of straight lines when projected.

10 3. A device of the class described comprising a casing, a davit normally retracted therein, said davit comprising articulate sections and means permitting limited relative movement of certain of the sections in projected position.

15 4. In combination with a hollow, rotatable casing, a motor carried thereby, means operable by the motor to rotate the casing, a davit normally disposed within the casing, and means to operate the davit from the motor.

20 5. In combination with a casing, a motor carried thereby, means operable by the motor to rotate the casing, a davit carried by the casing, means to project the davit from the casing, means on the davit to engage an object, and means to operate the last mentioned means from the motor.

25 6. A device of the class described comprising a casing, a davit normally housed within the casing, said davit comprising sections, means hinging said sections together, and link connections between the sections permitting limited movement thereof on their hinges.

30 7. A device of the class described comprising a casing, a davit normally disposed within the casing, said davit comprising articulated sections, and engaging elements carried by the sections and casing to guide the sections in retracted position.

35 8. A device of the class described comprising a casing, a davit normally disposed within the casing, said davit comprising articulated sections, engaging elements carried by the sections and casing to guide the sections in retracted position, means within the casing on which the davit normally rests, cable means operable to project the davit, and a resiliently mounted guide member within the casing below the davit traversed by said cable.

40 9. A device of the class described comprising a casing, a davit comprising articulated sections normally disposed within the casing, means mounting the casing for rotation, a rack concentric with the casing, a platform secured to and extending from the casing, a motor on said platform, a connection between the motor and rack whereby the same may rotate the casing, and means between the motor and casing operable to project the davit.

45 In testimony whereof I affix my signature.
LOWI EDWARDS.
